(57) CLAIM

The ornamental design for a dispensing device for drugs, as shown and described.

DESCRIPTION

FIG. 1 is a top, right and rear side perspective view of a dispensing device for drugs showing my new design;
FIG. 2 bottom, right and front side perspective view thereof;
FIG. 3 bottom, left and front side perspective view thereof;
FIG. 4 top, left and rear side perspective view thereof;
FIG. 5 is a rear elevational view thereof;
FIG. 6 is a left side elevational view thereof;
FIG. 7 is a front elevational view thereof;
FIG. 8 is a right side elevational view thereof;
FIG. 9 is a top plan view thereof; and,
FIG. 10 is a bottom plan view thereof.

The broken line showing in FIGS. 1, 2 and 8 are for illustrative purpose only and forms no part of the claimed design.
